UNITED STATES PATENT OFFICE

OTTO J. GROEHN, OF GROSSE POINTE PARK, MICHIGAN, ASSIGNOR TO HUDSON MOTOR CAR COMPANY, OF DETROIT, MICHIGAN, A CORPORATION OF MICHIGAN

APPARATUS FOR TRIMMING BODY PANELS

Application filed November 16, 1928. Serial No. 319,987.

This invention relates to a method and apparatus for trimming panels for automobile bodies and particularly back panels.

In certain other applications of mine, I have disclosed a method and apparatus whereby in the process of manufacturing automobile bodies it is possible to stamp out or draw from sheet metal, such as sheet steel, a single panel which when finished forms a convex back portion for the body as well as forwardly extending top and quarter side portions joined by upper spherical or ball corners. That is, a back panel unit is formed in a single drawing operation, the back portion of which being somewhat convex in shape and curving inwardly at its top to form a part of the top of the body and curving forwardly at its side edges to form the rear quarter portions of the body which extend over the rear wheel housings. Such a panel may form the entire back of the body as disclosed in my application Serial No. 276,635 filed May 10, 1928, or may form a substantial part of the back as disclosed in my application Serial No. 382,665 filed January 15, 1929.

After the back panel of the body has been drawn to the form and shape above described, the panel is trimmed in order to remove surplus metal preparatory to the flanging operation, the latter being shown and described in another application of mine. The present application relates to a method and apparatus whereby the entire panel may be completely trimmed at all four sides thereof to the proper shape and configuration in a single machine and in a single operation, as a result of which invention very substantial advantages and benefits are obtained, particularly where production is conducted on a large scale.

It is an object of the present invention to provide a simplified and economical method of trimming such panels and particularly a back panel which forms a part of both sides and the top of the body whereby the surplus metal may be removed from all edges substantially simultaneously and trimmed along a substantially continuous line.

It is another object of the invention to provide a machine for this purpose.

The invention will be more clearly understood from the following description in conjunction with the accompanying drawings, in which:

Fig. 1 is a perspective view from the front of a machine embodying the invention; 55

Fig. 2 is a plan view of the same with the upper die removed;

Figs. 3 and 4 are sectional elevational views taken upon the lines 3-3 and 4-4 of Fig. 2; 60

Fig. 5 is a fragmentary view in perspective of one of the rear corners of the machine;

Fig. 6 is a fragmentary view in perspective of one of the front corners of the machine;

Figs. 7, 8 and 9 are front, rear and side elevational views respectively of the lower die; 65

Fig. 10 is a detail view in section taken upon the line 10-10 of Fig. 7;

Fig. 11 is a detail view in section taken upon the line 11-11 of Fig. 9; 70

Fig. 12 is a perspective view of a body panel trimmed in accordance with the invention; and

Fig. 13 is a perspective view of the rear portion of an automobile embodying the body panel trimmed in accordance with the invention. 75

The invention is illustrated by its application for trimming a panel shaped to form the entire rear portion of the body having 80 a back 5, a top 6 and quarter sides 7 (Fig. 12). A suitable machine for performing the trimming operation may comprise a base 8 having a bed portion 9 projecting upwardly therefrom and shaped to receive a previously 85 drawn back panel 10 for an automobile body having back, top and quarter portions. The base 8 is provided with projections 11 extending outwardly from the lower portion of its sides and is provided with a projection 12 90 extending outwardly from its lower front portion. Suitable slides 14 and 15 are mounted upon the projections 11 and 12 respectively so that they may move toward and away from the die portion 9 of the base. These 95 slides are guided in their movement toward and from the base by suitable guideways 16 secured upon the projections 11 and 12 in any suitable manner, as by bolts 17. Stops 18 are secured upon the edge of the projections 100

11 and 12, as by bolts 19, to limit the outward movement of the slides. An upper die member 20 is mounted for movement toward and away from the base 8 in any suitable manner (not shown) and is provided with guideways 21 adapted to receive guides 22 mounted upon the projections of the base. The downward movement of the upper die 20 is limited by stop 23 upon the base.

10 Suitable cams 24 and 25 depend from the upper die 20 and are secured thereto in any suitable manner as by bolts 26. Each of these cams is provided with an inclined cam surface adapted to cooperate with an inclined cam surface 27 upon the slides 14 and 15 whereby downward movement of the upper die 20 causes an inward movement of the slides 14 and 15 toward die portion 9 of the base. Suitable guides 28 are secured adjacent the inclined cam surfaces 27 and are spaced therefrom but overlap the same whereby engagement therewith of the cams 24 and 25 during upward movement of the upper die 20 causes the slides 14 and 15 to move 15 away from the base.

20 The die portion 9 is provided with hardened blocks 30 upon the rear corners thereof which are shaped corresponding to the desired shape of the bottom portion of the panel to be trimmed and constitute knife edges adapted to cooperate with a similarly shaped knife 31 integral with or otherwise appropriately secured upon the upper die 20. The upwardly projecting portion of the 25 base has one or more rests 33 secured upon its rear portion as by screws 34 and shaped at 33a to receive a positioning rib formed near the bottom edge of the previously shaped panel to be trimmed, as best shown in Figs. 4 and 5.

40 The front of the die portion of the base is provided with hardened blocks 40 secured thereto in any suitable manner as by bolts 41 and forming a knife edge suitably shaped 45 for cooperation with a knife 42 mounted upon the slide 15 to trim the top 6 of the panel. One or more dowel pins 43 extend forwardly from the upwardly projecting portion of the base and are adapted to be received in suitable guide openings 44 in the slide 15 to guide the latter accurately in its movement. Cooperating with the cutting die 42 are a series 50 of plungers 35 provided with heads 36 slidably mounted within cavities 37 in the base. 55 These plungers extend freely through holes 38 in the cutter blocks 40 (Figs. 4 and 10), and are held yieldingly in extended position by springs 39 in the cavities 37 engaging the heads of the plungers. As later explained, 60 the plungers or ejectors 35 operate to eject the waste metal after the trimming operation.

65 The bottom and side edges of the inner face of the slides 14 are provided with hardened blocks 50 serving as a cutting die or knives cooperating with hardened cutting

blocks 51 secured upon the die portion of the base, as by bolts 52, to trim the quarter side portions 7 of the panel. A presser plate 53 is secured yieldingly upon the inner face of each slide 14, as by bolts 54, and normally is urged outwardly away from the slides 14 by springs 56 extending between oppositely located cavities 57 and 58 in the slide 14 and plate 53 respectively. The presser plate 53 is offset around its edge at 53a (see Fig. 3) 70 providing a pressing face cooperating with the cutting die 51 to clamp the panel adjacent the line of shearing or trimming, the clamping action being yielding by virtue of the springs 56.

75 Devices are provided for ejecting the waste metal at the junction R (Fig. 12) adjacent the point where the cut formed by the side cutting dies 50 and 51 intersects the cut made by the front cutting dies or knives 42 and 40. As shown in Figs. 6 and 11, these devices 80 each comprise a plunger 35a having a head 85 slideable against a compression spring 37a within a bore or cavity 39a in the base.

85 The waste metal between the points V and Q' is ejected by means of a spring actuated ejector plate 45. This plate 45 is movably mounted upon the side of the base adjacent the hardened blocks 51 as by means of bolts 46 and normally is held in extended position 90 by springs 47 extending between recesses 48 and 49 in the plate 45 and base respectively (Figs. 5, 8 and 9). As the cutting die 50 moves inwardly it engages the plate 45, forcing it inwardly to compress the springs. 10

95 The die portion 9 of the base is provided with a cavity 60 in its top surface to the bottom of which a plate 61 is secured, as by bolts 62. Spaced hardened blocks 63 are mounted upon the plate 61, as by bolts 64, and serve 100 as knife edges cooperating with knives 65 secured upon the upper die member 20, as by bolts 66, for trimming the rear window opening 67 in the panel. A presser plate 70 is movably mounted between the blocks 63, 11 as by bolts 71, and is held in extended position by springs 72 extending between recesses 73 and 74 in the plate 70 and blocks 63 respectively. The plate 70 is provided with an opening 75 to provide clearance for a positioning pin 76 projecting upwardly from the plate 61. A presser plate 80 is movably mounted upon the lower surface of the upper die member 20, as by bolts 81, and is provided with a plurality of projections 82 adapted 12 to engage the panel and hold the same snugly upon the die portion 9 of the base. The plate 80 is pressed yieldingly against the panel by springs 83 extending between cavities 84 and 85 in the upper die member 20 and plate 80 12 respectively, a groove 86 being provided in the plate 80 to receive the bead molding M upon the previously formed panel.

13 In operation the previously shaped panel 10 is placed upon the die portion of the base

with the pin 76 passing through an opening therein and with the rib on the bottom portion thereof fitted upon the rear rests 33. The upper die member 20 is then caused to move downwardly toward the lower die whereupon the presser plate 80 is brought into yielding engagement with the panel to hold the latter snugly upon the base. At the same time cams 24 are brought into engagement with the inclined cam surfaces 27 upon the slide 15 moving the latter inwardly to cause the knives 42 to cooperate with the blocks 40 to trim the top 6 of the panel. During this movement the knives 65 cooperate with the blocks 63 to trim the window opening 67 in the panel and the knife 31 cooperates with the hardened blocks 30 to trim the bottom portion of the panel. Thereafter, upon further downward movement of the upper die 20 the slides 14 are moved by engagement of the cams 25 therewith to cause the knives 50 to cooperate with the blocks 51 to trim the quarter portions 7 of the panel, clearance for the knives 50 being provided by pockets 77 in the edges of slide 15.

Referring now to Fig. 12, wherein the back panel P comprises a back portion 5, a forwardly extending top portion 6, forwardly extending quarter sides 7, it will be seen that the trimming or cutting mechanism is constructed and operated to trim or cut the top, bottom and sides on a continuous line with all of the cuts or trimming steps carried out substantially simultaneously.

The cutting die or knives 42 operate in a horizontal path forming a single continuous cut across the top portion 6 substantially on a line terminating at the points TT'. At the same time the side working cutting dies or knives 50, at opposite sides, each produce on a continuous line a horizontal cut QR intersecting the cut TT', a substantially vertical cut RS, a horizontal cut SV along the outer edge of the side, and a substantially vertical cut VQ'. The cutting die or knives 31 operating simultaneously in a vertical path produce an angular cut BCD intersecting the cut VQ', and also trim the bottom of the panel back along the line DD' (see Figs. 5 and 8). Thus, these knives cooperate to trim the edge of the panel along a substantially continuous line in a single operation, a very slight gap being left between the intersections Q' and B by a minute clearance between the adjacent edges of the knives 31 and 50. The upper die 20 is then caused to move upwardly away from the base in the course of which the trimmings are ejected from the cutting zone and the slides 14 and 15 are caused to move away from the die portion of the base by engagement of the cams 24 and 25 with the guides 28.

Referring to Figs. 4 and 10, it will be noted that as the knife 42 coacts with the knife 40 to trim along the line TT', the ejectors 35

will be forced inwardly by the knife 42, compressing springs 39. After the trimming operation the ejectors will be forced outwardly by the springs ejecting the waste metal. In like manner the waste metal at other cutting points will be ejected by the plungers 35a and the ejector plates or plungers 45. These plungers 35a and 45 are operated by the side cutting dies 50 and act at points adjacent the points of intersection of the cuts made by the several cutting dies or knives 42, 50 and 31.

I claim:

1. In a machine for trimming a back panel for an automobile body having back, top and quarter portions, the combination of a base having a die portion projecting upwardly therefrom adapted to receive said panel, an upper die member movable toward and away from the base, a presser foot yieldingly mounted upon said upper die member and arranged to engage and hold the panel positioned upon the die portion of said base, a plurality of slides movably mounted upon said base, a knife mounted on each slide, and a cam mounted on said upper die member adapted to engage and move said slides to trim the top and quarter portions of said panel along a substantially continuous line.

2. In a machine for trimming a back panel for an automobile body having back, top and quarter portions, the combination of a base having a die portion projecting upwardly therefrom adapted to receive said panel, an upper die member movable toward and away from the base, a presser foot yieldingly mounted upon said upper die member and arranged to engage and hold the panel positioned upon the die portion of said base, a knife mounted upon said upper die, a plurality of slides mounted upon said base to move toward and away from said lower die, a knife mounted on each slide, and means for moving said slides and upper die, said knives cooperating to trim the top, back and quarter portions of said panel along a substantially continuous line.

3. In a machine for trimming a back panel for an automobile body having top and quarter portions, the combination of a base having a die portion projecting upwardly therefrom adapted to receive said panel, slides mounted on said base for movement toward and away from adjacent sides of said die portion, a knife mounted on each of said slides, and means for moving said slides in timed relation, one of said slides being provided with a pocket adapted to receive the knife on an adjacent slide during the trimming operation, said knives cooperating to trim said panel along a substantially continuous line.

4. In a machine for trimming a back panel for an automobile body having a convex back portion and forwardly extending top and side portions, the combination of a pair of

- 5 cutting dies operating in paths at right angles to each other for forming a continuous cut in said top and side portions, one of said dies also operating to form a cut at right angles to said cut and joining the same.

5 6. In a machine for trimming a back panel for an automobile body having a convex back portion and forwardly extending top and side portions, the combination of a pair of cutting dies operating in paths at right angles to each other for forming a continuous cut in said top and side portions, one of said dies also operating to form a cut at right angles to said cut and joining the same, and means cooperating with said last named die for ejecting the excess metal adjacent the juncture of said cuts.

10 7. In a machine for trimming a back panel for an automobile body having a convex back portion and forwardly extending top and side portions, the combination of a pair of cutting dies operating in paths at right angles to each other for forming a continuous cut in said top and side portions, one of said dies also operating to form a cut at right angles to said cut and joining the same, and a spring mounted plunger cooperating with said last named die for ejecting the waste metal.

15 8. An apparatus for trimming a back panel for an automobile body having a convex back portion and forwardly extending top and side portions, the combination of a pair of cutting dies movable at right angles to each other, means for operating said dies simultaneously, said dies having means for forming intersecting cuts in the same plane in the top and side portions of the panel, and one of said dies also having means for forming a transverse cut in the side portion forming a continuation of said first cuts.

20 9. An apparatus for trimming a back panel for an automobile body having a convex back portion and forwardly extending top and side portions, the combination of a pair of cutting dies movable horizontally at right angles to each other, means for operating said dies simultaneously, said dies having means for forming intersecting cuts in the top and side portions of the panel, one of said dies also having means for forming a transverse cut in the side portion forming a continuation of said first cuts, and means located at the junction of the transverse and intersecting cuts for ejecting the waste metal.

25 10. In an apparatus for trimming the back panel of an automobile body having a convex back portion and forwardly extending top and side portions, the combination of a pair of cutting dies movable at right angles to each other for forming intersecting cuts in the top and side portions on a continuous line, one of said dies having means for forming a cut in the lower part of the side portion, a cutting die movable vertically for forming a cut in the lower part of the back portion and intersecting said last named cut, devices cooperating with one of said dies and acting at the junctions of certain of the cuts to eject the waste metal, and means for operating all of said dies simultaneously.

30 11. In an apparatus for trimming the back panel of an automobile body having a convex back portion and forwardly extending top and side portions, the combination of a pair of cutting dies movable horizontally at right angles to each other for forming intersecting cuts in the top and side portions on a continuous line, one of said dies having means for forming a cut in the lower part of the side portion, a cutting die movable vertically for forming a cut in the lower part of the back portion and intersecting said last named cut, spring controlled plunger devices acting adjacent the intersections of the cuts for ejecting the waste metal, and means for operating all of said dies simultaneously.

35 12. In an apparatus for trimming the back panel of an automobile body having a convex back portion and forwardly extending top and side portions, the combination of means for supporting the panel with the back portion substantially horizontal, a pair of cutting dies movable horizontally at right angles to each other for forming intersecting cuts in the top and side portions on a continuous line, one of said dies having means for forming a cut in the lower part of the side portion, a cutting die movable vertically for forming a cut in the lower part of the back portion, and intersecting said last named cut, a cutting die movable vertically for cutting a window opening in said back portion, and means for operating all of said dies simultaneously.

40 13. In testimony whereof I affix my signature.

45 OTTO J. GROEHN.
